UNITED STATES PATENT OFFICE.

WILLIAM J. GRIFFIN, OF PHILADELPHIA, PENNSYLVANIA.

QUICK CLAMP AND DRILL GUIDE.

Application filed May 21, 1920. Serial No. 383,093.

To all whom it may concern:

Be it known that I, WILLIAM J. GRIFFIN, a citizen of the United States, residing at Philadelphia, in the county of Philadelphia and State of Pennsylvania, have invented new and useful Improvements in Quick Clamp and Drill Guides, of which the following is a specification.

My invention relates to a new and useful improvement in quick clamp and drill guides, and has for its object to provide an exceedingly simple and effective device of this description which may be readily applied to the object to be drilled, such as the hull of a ship for setting and holding a drill.

A further object of my invention is to utilize the reinforcement or frame of a port hole or the like which has previously been fabricated including the bolt holes drilled therein as a jig for positioning the drill to form corresponding holes in the hull of the ship so that both set of holes will accurately align.

A further object of my invention is to so construct the device that the port hole reinforcement or frame will accurately center the clamp.

A still further object of my invention is to provide for the quick adjustment of the parts to economize time in placing and removing the device.

With these ends in view, this invention consists in the details of construction and combination of elements hereinafter set forth and then specifically designated by the claim.

In order that those skilled in the art to which this invention appertains, may understand how to make and use the same, I will describe its construction in detail, referring by numerals to the accompanying drawing forming a part of this application, in which:

Fig. 1, is a plan view of my improved clamp applied to a porthole showing the reinforcement or frame in position.

Fig. 2, is a central section of the port hole or frame and a portion of the hull of a ship showing my device in elevation and applied thereto.

Fig. 3, is an enlarged perspective of the upper clamping bar.

Fig. 4, is a view similar to Fig. 3 of the lower clamping bar.

55 In carrying out my invention as here embodied, 1 represents the post of what is

known in the trade as an "old man," and the lower portion of this post is threaded for the reception of the wing nut 2, the wings 3 thereof being of sufficient length to give the 60 proper purchase for clamping purposes.

4 represents the upper clamp bar having the heads 5 formed upon each end thereof, each head being provided with the lips 6 and 7 the distance between the lips 7 being 65 of less diameter than the distance between the lips 6 for the purpose hereinafter explained. This bar has an enlargement 8 at the central portion thereof through which is formed the hole 9 of sufficient size to pass 70 over the threaded end of the post in order that the hand nut 2 may be brought to bear upon said enlargement.

10 represents the lower clamp bar having its ends turned upward as indicated at 11 75 for contact with the outside of the plate 12 of the ship's hull, and this bar also has its center enlarged as indicated at 13, and a threaded hole 14 formed therethrough for running upon the threaded end of the post. 80 When the bar 10 is run upon said post it is held against displacement by the set screw 15 which is threaded through a suitable hole in the central enlargement of the bar, and the post is provided with a groove 15^a for 85 the reception of the end of the set screw to prevent the burring of the threads upon the post which would otherwise take place if a set screw contacted with said threads.

16 represents the arm of the "old man" 90 having a hub 17 and a hole 18 formed therethrough for passage over the upper end of the post, and this hub is provided with the ears 19 which are separated by the slot 20 in order that the hub may be rigidly 95 clamped upon the post in any adjustment, the clamping means consisting of a bolt 21 passed through suitable holes in ears and having a nut 22 run thereon, said bolt terminating in a hand lever 23 for its operation.

24 represents the port hole reinforcement or frame which has formed therein the bolt holes 25, and which when clamped in place upon the ship's hull serves as a jig for placing and guiding the drill.

From the foregoing description the operation of my improvement will be obviously as follows:

The frame 24 being set in place upon the 110 ship's hull so as to align with the port hole 26 the clamp bars 4 and 10 are set at sub-

stantially right angles to each other when the lower clamp bar 10 may be readily passed through the port hole by tilting the device at the proper angle, and when this bar has been brought in contact with the inside of the plate 12 the clamp 4 is brought into position so that the lips 6 or 7 (shown as the former) fit over the outer circumference of the frame 24 thus positioning the clamps after which by 10 screwing up upon the hand nut 2 the clamp bars will be drawn toward each other and the frame 24 securely held in position and likewise rigidly setting the "old man." After this has been accomplished the arm 16 15 is swung over one of the holes 25 and the drill plates in position, the bit thereof passing into the hole 25 so that the operation of the drill will thereafter bore a hole through the plate 12 in exact alignment with the hole 25. This operation 20 is repeated by turning the arm 16 from one hole to another until all of the holes have been drilled through the plate 12 to correspond with the number of holes 25 in the 25 port hole frame.

After the drilling has been accomplished the clamp bars may be left in position until two or more bolts have been set thus preventing any shifting of the port hole frame, and 30 thereby saving considerable time and labor.

When port hole frames of smaller diameter are used the clamps 4 are reversed upon the post so as to bring the lips 7 into active position, thus making the device capable of use upon port hole frames of two sizes and when a further variety of port hole frames are met with, one or more other clamp bars 4 may be utilized having the lips 6 and 7 differently spaced from those shown, 35 thus giving the device a wide range and as the parts thereof are quickly adjustable a great saving is effected.

One of the marked advantages of my improvement is that the device may be applied

to the object in which the holes are to be 45 drilled from one side and in case of ship-building this is a great advantage since a second workman does not have to go outside of the hull for placing clamps for holding the "old man" as the work can be done entirely from the inside of the hull. 50

Another marked advantage of my improvement is that as the clamp bars 4 and 10 may be placed at substantially right angles to each other when the device is secured 55 in place, these clamp bars brace the post in every direction giving great rigidity to the arm 16 for facilitating the operations of the drill.

Of course I do not wish to be limited to the 60 exact details of construction as herein shown as these may be varied within the limits of the appended claim without departing from the spirit of my invention.

Having thus fully described my invention, 65 what I claim as new and useful:—

A device of the character stated adapted to be clamped across a port hole in a structure comprising in combination, a clamp bar adapted to bridge the port hole, two lips 70 at each end of the bar projecting in opposite directions and located different distances from the center of said bar, said lips adapted to engage the edges of a frame surrounding the port hole, a post passing through the 75 center of the clamp bar, a second clamp bar adapted to bridge the port hole and having upturned end to engage the structure in the region of the port hole, said second named clamp bar having threaded connection with 80 the post and means also having threaded connection with the post and adapted to engage the first mentioned clamp bar for drawing said clamp bars toward each other.

In testimony whereof, I have hereunto 85 affixed my signature.

WILLIAM J. GRIFFIN.
